DESIGN FOR A PASSENGER LOADING RAMP

Albert L. Varrieur and Charles E. Hollyday, Jr.
Baltimore, Md., assignors to The Glenn L.
Martin Company, Baltimore, Md.

Application March 1, 1946, Serial No. 127,022

Term of patent 14 years

(Cl. D14—3)

To all whom it may concern:

Be it known that we, Albert L. Varrieur and Charles E. Hollyday, Jr., citizens of the United States and residents of city of Baltimore, State of Maryland, have invented a new, original, and ornamental Design for a Passenger Loading Ramp, of which the following is a specification, reference being had to the accompanying drawings, forming part thereof.

Figure 1 is a perspective view of a passenger

loading ramp showing our new design as it appears when seen from one side thereof.

Figure 2 is a perspective view showing the side opposite that illustrated in Figure 1.

We claim:

The ornamental design for a passenger loading ramp, substantially as shown.

ALBERT L. VARRIEUR.
